CLAIM

The ornamental design for a roasting skewer stand, as shown and described.

DESCRIPTION

FIG. 1 is a perspective view of the present invention;

FIG. 2 is a front view in elevation thereof;

FIG. 3 is a rear view in elevation thereof;

FIG. 4 is a left side view in elevation thereof;

FIG. 5 is a right side view in elevation thereof; and,

FIG. 6 is a top plan view thereof; and,

FIG. 7 is a bottom plan view thereof.

The broken lines shown in the drawings are for illustrative purposes only and form no part of the claimed design.
